UNITED STATES PATENT OFFICE.

EUGENE BROWN, OF COLFAX, WASHINGTON, ASSIGNOR OF ONE-SIXTH TO GEORGE A. CHAPMAN AND ONE-SIXTH TO CHARLES E. SCRIBER, OF COLFAX, WASHINGTON, AND ONE-SIXTH TO WILBUR S. YEARSLEY, OF SPOKANE, WASHINGTON.

ROLLER-MILL.

No. 888,581.

Specification of Letters Patent.

Patented May 26, 1908.

Application filed May 20, 1907. Serial No. 374,675.

To all whom it may concern:

Be it known that I, EUGENE BROWN, citizen of the United States, residing at Colfax, county of Whitman, and State of Washington, have invented certain new and useful Improvements in Roller-Mills, of which the following is a specification, reference being had therein to the accompanying drawing.

10 This invention relates to a roller mill, and particularly to a construction embodying a bed and roller coöperating therewith to roll the grain instead of grinding the same.

The invention has for an object to provide 15 a novel and improved construction of the roller and bed whereby a crushing action of the grain is secured in the movement of one of the parts upon the other and a grinding avoided so that the grain is left in flat pieces 20 having all of its parts together.

A further object of the invention is to provide an improved construction and arrangement of parts to remove the grain from the bed and deliver it to a trough from 25 which it may be discharged at any desired point.

Other and further objects and advantages of the invention will be hereinafter set forth and the novel features thereof defined by 30 the appended claims.

In the drawing:—Figure 1 is an elevation showing the invention; Fig. 2 is a horizontal section on the line 2—2, Fig. 1; Fig. 3 is a detail horizontal section of one of the rolls 35 with the casing removed therefrom; Fig. 4 is a vertical section of the parts shown in Fig. 3, and Fig. 5 is a detail perspective of the scraper and brush mounted upon the shaft of the crushing roller.

40 Like numerals refer to like parts in the several views of the drawing.

The numeral 1 designates the base of the machine which may be of any desired size or construction upon which the bearing standards 2 are mounted, these being sufficient 45 in number to accommodate the number of crushing rolls 3 used in the mill. At the lower portion of these standards a shaft 4 is pivotally mounted and carries sup-

porting wheels 5 upon which the body of 50 the annular bed 6 is carried. These wheels 5 permit the free rotation of the bed in its travel. This travel is accomplished by mounting upon one or more of the shafts 4 a driving gear 7 which meshes with coöper- 55 ating teeth 8 upon the under face of the bed, and the shaft is driven from any desired power by means of pulley 9 upon the outer end thereof. The bed is retained against lateral play or movement by means of a 60 bearing roll 10 mounted in the standard opposite the periphery of the bed upon the stud 11 provided for that purpose.

The outer periphery of the bed 6 is provided with the vertical flange 12 to retain 65 the grain thereon, and the surface of the bed is substantially horizontal, as shown at 13, while disposed at the inner periphery of the bed and supported from the standards 2 is a delivery trough 14 into which the crushed 70 grain is scraped as hereinafter described. Mounted upon the traveling bed and disposed within the trough is a collecting plate 15 which carries the grain in the trough to the proper point for delivery. The roll 3 is 75 preferably tapered from its inner edge outwardly, as shown in Fig. 4, and the shaft 16 of this roll is inclined diagonally to the bed so as to present the crushing surface of the roll in proper position to prevent any differential movement between these parts which would result in a grinding action, and to perform a crushing of the grain by the movement of the bed and the imparted movement of the roll. The roll 3 is supported under tension 80 in contact with the bed by means of the tension springs 17 extending from the bearing blocks 18 to the cross piece 19 at the top of the standards at which point a proper tension screw 20 is mounted to adjust these 85 springs. The bearing blocks 18 are each provided with curved surfaces disposed at the proper angle to fit the inclination of the shaft 16.

The scraper 21 is supported from the shaft 95 16 of the roll and at an inclination to the longitudinal axis thereof by means of the arms 22 provided with collars 23 to embrace

the shaft 16. Mounted between these arms is a brush 24 adapted to engage the face of the roll 3 and remove adhering grain therefrom. This brush is capable of adjustment 5 toward and from the roll by means of the slots 25 in the arms and the retaining screw 26 extending through said slots into the brush block. The end of this scraper extends into the trough 14 to insure a positive delivery 10 of the grain thereto.

The grain is fed to the bed at one side of the roller from a tank or bin 27 mounted upon supports 28 at the top of the standards, and from this bin is carried through chutes 29 to 15 the delivery spout 30 disposed immediately adjacent to the upper surface of the bed. These spouts are provided with any desired construction of cut off valve 31 which may be adjusted to the desired extent to determine 20 the feed. Each of the rolls is disposed within a protecting casing 32 mounted upon the standards, in any desired manner. A guard plate 33 is disposed at the inner edge of the bed and supported upon the standards so as 25 to retain the grain within the area of the roll during the crushing action. The casing is also provided with a hinged or pivoted section 34 at the side next the cleaning brush so as to permit access thereto when desired.

30 In the operation of the invention the grain is fed from the bin through the chutes on the bed immediately adjacent the crushing roll which owing to its disposition relative to the revolving bed crushes or mashes the grain 35 into flattened condition and it is then scraped therefrom into the delivery trough. This particular arrangement of the roll prevents any grinding or tearing action of the grain by dragging it over the bed and insures a 40 maximum amount of work for the capacity of machine employed. The brush and scraper effectually clear the bed of the crushed grain and also clean the roll of adhering material so that it is in condition for subsequent use.

45 The invention therefore presents a simple and economical construction of roller mill adapted to most efficiently accomplish the functions of such a device, in which each roll acts independently and the rolls may be multiplied dependent upon the area of the bed to 50 increase the capacity of a machine.

Having described my invention and set forth its merits, what I claim and desire to secure by Letters Patent is:—

55 1. In a roller mill, an annular bed disposed in a horizontal plane, means for rotating the same, an inwardly tapered roller supported in contact with said bed, a feeding device disposed at one side of said roller, a delivery 60 trough at the inner edge of said bed, and a scraper supported to traverse said bed and extend over said trough.

2. In a roller mill, an annular bed, a coöp-

erating roller mounted thereon, a fixed trough supported at the inner edge of said 65 bed, a scraper extended across the bed and over said trough to deliver thereto, and a collecting device carried by the bed to traverse said trough.

3. In a roller mill, an annular bed, a coöperating roller mounted upon said bed, a fixed trough supported at the inner periphery of said bed, a collecting device carried by the bed and extended into said trough to traverse the same, a scraper supported from the 75 shaft of said roller and extending over the bed and trough, and a brush carried by the scraper support intermediate the scraper and roller to contact with the crushing face of the 80 roller.

4. In a roller mill, a bed having an annular crushing face disposed in a horizontal plane, an inwardly tapered roll disposed with its crushing face parallel to said bed face, a shaft for said roll disposed diagonally to the crushing face of the bed, opposite standards for supporting said shaft, a supporting wheel mounted in said standards beneath said bed, and means for discharging crushed material 85 at the inner edge of said bed.

90 5. In a roller mill, standards, an annular bed mounted to rotate between said standards, a roller mounted in the standards to traverse said bed, parallel supporting arms extended from the shaft of said roller, and an 95 inclined scraper carried by the free end of said arms adjacent to the face of said bed.

6. In a roller mill, standards, an annular bed mounted to rotate between said standards, a roller mounted in the standards to 100 traverse said bed, parallel supporting arms extended from the shaft of said roller, an inclined scraper carried by the free end of said arms adjacent to the face of said bed, a brush and means for adjustably mounting the 105 brush upon said arms to engage the periphery of said roller.

7. In a roller mill, a series of standards, an annular bed mounted to pass between said standards, supporting means for said bed, 110 rollers coöperating with said bed and supported by said standards, a feed bin carried by the upper portion of said standards, chutes depending from said bin adjacent to one side of each of said rollers, a delivery 115 trough mounted at one edge of said bed, and a scraper carried by said rollers at the opposite side from the chute to deliver into said trough.

8. A roller mill comprising a series of 120 standards, an annular bed mounted to pass between said standards, supporting means for said bed, rollers coöperating with said bed and supported by said standards, a feed bin carried by the upper portion of said standards, chutes depending from said bin adja-

cent to one side of said rollers, a delivery trough mounted at one edge of said bed intermediate of adjacent standards, a scraper carried by said rollers to deliver into said 5 trough, a collecting plate carried by the bed to traverse said trough, and a curved guard plate mounted upon one standard and extending at each end over the delivery trough

and with an intermediate portion opposite the inner side of the roller.

In testimony whereof I affix my signature 10 in presence of two witnesses.

EUGENE BROWN.
